Specification for Design.

Patented May 30, 1916.

Application filed April 8, 1916. Serial No. 90,005. Term of patent 3½ years.

To all whom it may concern:

Be it known that I, CHARLES E. JONES, a citizen of the United States, residing at Chicago, in the county of Cook and State of Illinois, have invented a new, original, and ornamental Design for an Arm-Husk or Body for Electric Brackets and Chandeliers, of which the following is a specification, reference being had to the accompanying drawing, forming part thereof.

Figure 1 is a top view of an arm husk or body for electric brackets and chandeliers, showing my new design. Fig. 2 is a front view of the same. Fig. 3 is a side view of the same.

I claim:

The ornamental design for an arm husk or body for electric brackets and chandeliers, as shown.

CHARLES E. JONES.
